CALCULATOR

Jorge Quijano, Mexico, Mexico

Application December 30, 1929, Serial No. 417,454, and in Mexico December 31, 1928.
Renewed August 25, 1932

8 Claims. (Cl. 235—64)

This invention relates to a calculator, one of the objects being to provide a simple, compact and efficient device of this character which can be conveniently located on a pencil, pen holder or other similar article.

A further object is to provide a calculator by means of which simple mathematical problems can be solved.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings the preferred form of the invention has been shown.

20 In said drawings:

Figure 1 is a plan view of the calculator in position on a lead pencil or the like which is broken away.

Figure 2 is a similar view showing the number 25 rings in section.

Figure 3 is a section on line 3—3, Figure 1, the pencil or the like being shown in elevation.

Figure 4 is a plan view of the core.

Figure 5 is an end elevation of the complete 30 structure.

Figure 6 is a section on line 6—6, Figure 1.

Figure 7 is a perspective view of one of the inner rings.

Figure 8 is a perspective view of one of the 35 number rings.

Figure 9 is a plan view of the sleeve.

Figure 10 is a development of the sleeve showing the columns of characters provided thereon.

Figure 11 is a development of a portion of 40 the sleeve and one of the number rings showing said ring positioned to solve a problem in multiplication.

Referring to the figures by characters of reference, 1 designates the core of the calculator 45 which can be solid or tubular and of any desired cross sectional contour although it is preferred to make it cylindrical. As shown in Figure 3 this core can receive a pencil, pen holder or other device indicated at P.

50 Extending outwardly from the core is a longitudinal series of studs 2 which can be made of separate pins driven into the core as shown or can be of any other suitable construction. These pins project through a longitudinal slot 3 provided 55 in a sleeve 4 which is slidable longitudinally along

the core 1 and is provided, on its outer surface, with parallel columns of characters which extend around the sleeve from one side to the other of the slot. As shown particularly in Figure 10, fifteen of these columns have been provided. 60 These columns are designated by the headings "9U", "9T", "8U", "8T", "7U", "7T", "6U", "6T", "5U", "5T", "1U", "4U", "4T", "3U", and "3T". In addition to these column designating characters each column contains the numerals "1" to 65 "9", the numerals in each column being differently arranged for the purpose of producing the desired results from the calculating process. For the sake of compactness some of the column designating characters are located at one end of the 70 columns while the remaining ones are located at the other end of the columns.

Mounted for rotation on the sleeve 4 are inner rings 5 which extend between the ends of the studs 2. Each of these inner rings has a lug 6 75 extending from one edge for abutment against one of the studs while formed in the opposite edge is a notch 7. The rings are so proportioned and positioned relative to the pins that after substantially one complete rotation of a ring has 80 been completed, the lug 6 will come against the adjacent stud 2 so that further rotation will be prevented unless ring 5 is shifted axially. This will cause the notch 7 to receive the adjacent stud and allow the lug 6 to pass the stud in the 85 path thereof.

Secured upon and rotatable with each of the inner rings 5 is a number ring 8 one edge of which is formed with ten regularly spaced notches 9 while extending from the other edge is a coupling finger 10. Each ring is provided with an annular series of ten numerals ranging in regular succession from "1" to "0". The "0" character is located in line with the finger 10 and the finger is of such length that when the rings 5 are 90 in their normal positions on sleeve 4 said finger will have sliding contact with the notched edge of the next adjoining ring as shown, for example, in Figure 1.

When it is desired to solve a problem in addition the ring 8 at the right of the calculator is turned in the direction indicated by the arrow in Figure 1 until the numeral "9" is brought to the position previously occupied by the character "0" at which time the lug 6 will be stopped 100 by contact with stud 2 in the path thereof. The sum can then be carried over into the next column by shifting ring 8 and its inner ring 5 axially so as to move finger 10 into the notch 9 aligned therewith and withdraw lug 6 from 105 110

engagement with stud 2. The rings can then be moved one space at which time they will be coupled together after which the first or "unit" ring can be slid back to its initial position. Thus 5 it will become uncoupled from the "tens" ring and the "unit" ring can again be rotated after which the foregoing operation can be repeated. Thereafter the "tens" ring can be similarly shifted to couple with the "hundreds" ring. Thus a 10 problem in addition can be carried out until all of the rings have been brought into play.

For adding together 3, 4, 5, for instance, first, the character 0 on each of two rings at the right, is brought into alinement with the heading 1U 15 as shown in the following diagram, 1st, 2d, 3d columns representing 1st, 2d, 3d, rings and small letters on the diagram not being found in the drawings.

Rings			
20	Columns in Fig. 10	3d	2d 1st
1	1U 5 12	3U . . . 0	0 0
23	1 34	7 . . . 1	1 1
45	2 38 567	4 . . . 2	2 2c
67	3 89	1 . . . 3	3 3a
89	4 16	8 . . . 4	4 4
	5	5 . . . 5	5 5
	6 49	2 . . . 6	6 6
	7	9 . . . 7	7 7b
	8 27	6 . . . 8	8 8
36	5T 9 4U 4T	3 . . . 9	9 9

Then the point "a" of the first ring at the right which is now alined with digit 3 on the column corresponding to said heading 1U, is brought into alinement with same heading 1U, and thereby the numeral 3 on said first ring is alined with heading 1U as shown in the following diagram:

Rings			
40	Columns in Fig. 10	3d	2d 1st
1	1U 5 12	3U . . . 0	0 3a
23	1 34	7 . . . 1	1 4
45	2 38 567	4 . . . 2	2 5
67	3 89	1 . . . 3	3 6
89	4 16	8 . . . 4	4 7b
	5	5 . . . 5	5 8
	6 49	2 . . . 6	6 9
	7	9 . . . 7	7 0
	8 27	6 . . . 8	8 1
50	5T 9 4U 4T	3 . . . 9	9 2c

Then the point "b" on same first ring which is now alined with digit 4 on said column 1U, is brought into alinement with said heading 1U, and thereby the numeral 7 on said first ring is alined with heading 1U as shown in the following diagram:

Rings			
60	Columns in Fig. 10	3d	2d 1st
1	1U 5 12	3U . . . 0	0 7b
23	1 38 34	7 . . . 1	1 8
45	2 38 567	4 . . . 2	2 9
67	3 89	1 . . . 3	3 0
89	4 16	8 . . . 4	4 1
	5	5 . . . 5	5 2c
	6 49	2 . . . 6	6 3a
	7	9 . . . 7	7 4
	8 27	6 . . . 8	8 5
70	5T 9 4U 4T	3 . . . 9	9 6

Then the point "c" on same first ring which is now alined with digit 5 on said column, 1U is brought into alinement with said heading 1U, and thereby numeral 2 on said first ring will be

alined with heading 1U, as shown in the following diagram:

Rings			
Columns in Fig. 10			
1	1U 5 12	3U . . . 0	1 2c
23	1 34	7 . . . 1	2 3a
45	2 38 567	4 . . . 2	3 4
67	3 89	1 . . . 3	4 5
89	4 16	8 . . . 4	5 6
	5	5 . . . 5	6 7b
	6 49	2 . . . 6	7 8
	7	9 . . . 7	8 9
	8 27	6 . . . 8	9 0
5T	9 4U 4T	3 . . . 9	0 1

90

In this diagram numeral 1 on the second ring appears now also in a line with heading 1U, because the first ring has moved more than one complete turn and the second ring has thereby been moved one space as above explained. 95

Such results 1 and 2 now appearing respectively on first and second ring, in a line with said heading 1U, are read together as 12, sum of 3, 4, 5.

Said results, 1 and 2, can also be read on column 9U in a line respectively with the 0 characters on first and second rings. Therefore all numerals on any ring can be omitted excepting one representing "0". Then columns identical to said column 9T can be printed between the rings, in order to read more easily results on 105 them.

In Fig. 10 the numerals 16, 48, 246, etc., do not mean respectively sixteen, forty eight, two hundred and forty six, etc., but they are read 1, 6; 4, 8; 2, 4, 6; etc., the digits of each column being 110 thus read separately, one by one, representing respectively digit factors, 1, 6, 4, 8, 2, 4, 6, etc. and marking respective distances proportional to the units of respective products and distances proportional to the tens of same respective products. 115

The following statements show exactly, completely and unmistakably by means of an example, how the tens and units of any product can be known and added separately without requiring from the operator previous knowledge or 120 remembrance of the product.

If any point of any ring is moved, for instance, from alinement with digit 8 found in column marked 7T, Fig. 10, into alinement with line marked 11 in Fig. 10, the ring is thereby moved 125 5 spaces corresponding to tens, 5 of product 56 of 8 by 7.

Likewise, if any point of any ring is moved from alinement with digit 8 found in column marked 7U, into alinement with said line marked 11 in Fig. 10, same ring is moved thereby 6 130 spaces corresponding to units 6 of said product 56 of 8 by 7.

It is not necessary to say that after moving the rings in such manner, it is sufficient to see 135 and count said 5 and 6 spaces, one by one for knowing such results, although I provide means for reading said results 5 and 6 without counting.

According to above example no further explanation is necessary to show how the tens and units of any product can be known and added separately without previously knowing or remembering the product. 140

Therefore the core, the rings, Fig. 6 and the 145 numerical arrangement, shown more clearly in Fig. 10, are sufficient to form a new useful combination.

However numeral graduation on the rings, coupling of rings to each other, sliding sleeve and 150

other features, are also important features to form new combinations and to complete the object of my invention.

Now, for multiplying for instance, 47 by 8, the character "0" of each ring is placed in a line with the heading 1U, according to the following diagram:

Columns in Fig. 10										Rings			Rings			Rings		
										3d	2d	1st	3d	2d	1st	3d	2d	1st
9	U	1	5	1	7	U	1	.	.	1	U	.	0	0	0	9	U	1
9	2	2	2	3	2	.	1	.	.	1	1	1	6	5	38	56	2	67
8	3	49	3	6	34	.	2	.	.	2	2	2	5	6	7	5	8	7
7	4	4	4	9	5	.	3	.	.	3	3	3	4	7	27	8	8	9
6	5	38	56	2	67	.	4	.	.	4	4	4	3	8	9	1	7	0
5	6	7	5	8	5	.	5	.	.	5	5q	5	2	9	16	4	8	9
4	7	27	8	8	9	.	6	.	.	6	6	6	1	9T	8U	8T	7T	7
3	8	9	1	7	7	.	7	.	.	7	7r	7	2	9	16	4	8	8
2	9	16	4	8	8	.	8	.	.	8	8	8	1	9T	8U	8T	7U	9
1	9T	8U	8T	7U	7U	.	9	.	.	9	9	9	9	9	9	9	9	9

Then the point "p" of the first ring at the right, which is now alined with digit 7 on the column 8U, is brought into alinement with heading 1U, resulting thereby that numeral 6 on same first ring will be alined with heading 1U as shown in the following diagram:

Columns in Fig. 10										Rings			Rings			Rings		
										3d	2d	1st	3d	2d	1st	3d	2d	1st
9	U	1	5	1	7	U	1	.	.	1	U	.	0	0	0	9	U	1
9	2	2	2	3	2	.	1	.	.	1	1	7	6	5	38	56	2	67
8	3	49	3	6	34	.	2	.	.	2	2	8	3	6	7	5	8	7
7	4	4	4	9	5	.	3	.	.	3	3	9	7T	1	9	3	3	3
6	5	38	56	2	67	.	4	.	.	4	4	0	2	2	4	4	4	4
5	6	7	5	8	5	.	5	.	.	5	5q	1	34	5	5	5	5	5
4	7	27	8	8	9	.	6	.	.	6	6	2	5	8	6	6	6	6
3	8	9	1	7	7	.	7	.	.	7	7r	3	67	1	7	7	7	7
2	9	16	4	8	8	.	8	.	.	8	8	4	8	4	8	8q	8	8
1	9T	8U	8T	7U	7U	.	9	.	.	9	9	5	9	7	9	9	9	9

Then the point "q" of the second ring which is now alined with digit 7 on the column marked 8T, is brought into alinement with the heading 1U, resulting thereby, that numeral 5 of said second ring will be alined with heading 1U as shown in the following diagram:

Columns in Fig. 10										Rings			Rings			Rings		
										3d	2d	1st	3d	2d	1st	3d	2d	1st
9	U	1	5	1	7	U	1	.	.	1	U	.	0	5q	6p	7U	1	U
9	2	2	2	3	2	.	1	.	.	1	1	7	3	6	7	5	8	7
8	3	49	3	6	34	.	2	.	.	2	2	8	6	5	38	56	2	67
7	4	4	4	9	5	.	3	.	.	3	3	9	7T	1	9	3	3	3
6	5	38	56	2	67	.	4	.	.	4	4	0	2	2	4	4	4	4
5	6	7	5	8	5	.	5	.	.	5	5q	1	34	5	5	5	5	5
4	7	27	8	8	9	.	6	.	.	6	6	2	5	8	6	6	6	6
3	8	9	1	7	7	.	7	.	.	7	7r	3	67	1	7	7	7	7
2	9	16	4	8	8	.	8	.	.	8	8	4	8	4	8	8q	8	8
1	9T	8U	8T	7U	7U	.	9	.	.	9	4	5	9	7	9	9	9	9

Then the point "r" of the second ring which is now alined with digit 4 on the column 8U is brought into alinement with the heading 1U, resulting thereby that numeral 7 on said second ring will be alined with heading 1U as shown in the following diagram:

Columns in Fig. 10										Rings			Rings			Rings		
										3d	2d	1st	3d	2d	1st	3d	2d	1st
9	U	1	5	1	7	U	1	.	.	1	U	.	0	7r	6p	7U	1	U
9	2	2	2	3	2	.	1	.	.	1	8	7	3	6	7	5	8	7
8	3	49	3	6	34	.	2	.	.	2	9	8	7	2	2	4	4	4
7	4	4	4	9	5	.	3	.	.	3	8	9	7	2	2	4	4	4
6	5	38	56	2	67	.	4	.	.	4	1	0	34	5	5	5	5	5
5	6	7	5	8	5	.	5	.	.	5	2	1	5	8	6	6	6	6
4	7	27	8	8	9	.	6	.	.	6	3	2	6	3	2	4	4	4
3	8	9	1	7	7	.	7	.	.	7	4	3	67	1	7	7	7	7
2	9	16	4	8	8	.	8	.	.	8	5q	4	8	4	8	8q	8	8
1	9T	8U	8T	7U	7U	.	9	.	.	9	6	5	9	7	9	9	9	9

Then the point "s" of the third ring which is now alined with digit 4 on the column marked 8T

is brought into alinement with heading 1U, resulting thereby that numeral 3 on said third ring will be alined with heading 1U as shown in the following diagram:

Columns in Fig. 10										Rings			Rings			Rings		
										3d	2d	1st	3d	2d	1st	3d	2d	1st
9	U	1	5	1	7	U	1	.	.	1	U	.	3s	7r	6p	7U	1	U
9	2	2	2	3	2	.	1	.	.	1	8	7	5	6	7	5	8	7
8	3	49	3	6	34	.	2	.	.	2	9	8	7	2	2	4	4	4
7	4	4	4	9	5	.	3	.	.	3	8	9	7	2	2	4	4	4
6	5	38	56	2	67	.	4	.	.	4	1	0	34	5	5	5	5	5
5	6	7	5	8	5	.	5	.	.	5	2	1	5	8	6	6	6	6
4	7	27	8	8	9	.	6	.	.	6	3	2	6	3	2	4	4	4
3	8	9	1	7	7	.	7	.	.	7	4	3	67	1	7	7	7	7
2	9	16	4	8	8	.	8	.	.	8	5q	4	8	4	8	8q	8	8
1	9T	8U	8T	7U	7U	.	9	.	.	9	6	5	9	7	9	9	9	9

is brought into alinement with heading 1U, resulting thereby that numeral 3 on said third ring will be alined with heading 1U as shown in the following diagram:

Columns in Fig. 10										Rings			Rings			Rings		
										3d	2d	1st	3d	2d	1st	3d	2d	1st
9	U	1	5	1	7	U	1	.	.	1	U	.	3s	7r	6p	7U	1	U
9	2	2	2	3	2	.	1	.	.	1	8	7	5	6	7	5	8	7
8	3	49	3	6	34	.	2	.	.	2	9	8	7	2	2	4	4	4
7	4	4	4	9	5	.	3	.	.	3	8	9	7	2	2	4	4	4
6	5	38	56	2	67	.	4	.										

The core is preferably hollow to inclose a pencil, fountain pen, slate pencil or other similar thing.

I have described means for carrying from a ring to next ring. Such means can be omitted and then, after each complete turn of the ring the operator will move next ring one space directly with his own hand for carrying over.

What I claim is:

- 10 1. A calculator including a core, rings rotatably mounted thereon and annular columns of characters around the core, said characters representing respective factors and marking along the columns distances proportional to the tens of the corresponding products and distances proportional to the units of same products.
- 15 2. A calculator including a core, rings rotatably mounted thereon, each ring having an annular series of numerals arranged progressively from "0", "1", . . . to "9" and annular columns of characters around the core, said characters representing and marking along the columns distances proportional to the tens of the corresponding products and distances proportional to the units of same products.
- 20 3. A calculator including a core, rings rotatably mounted thereon and a slidable sleeve having annular columns of characters, these characters representing respective factors and marking along the columns distances proportional to the tens of the corresponding products and distances proportional to the units of same products.
- 25 4. A calculator including a core, rings rotatably mounted thereon, each ring bearing an annular series of numerals arranged progressively from "0", "1" . . . to "9" and a sleeve having annular columns of characters, these characters representing respective factors and marking along the columns distances proportional to the tens of the corresponding products and distances proportional to the units of same products.
- 30 5. A calculator including a core, rings rotatably mounted thereon, a non-rotatable sleeve slidable along the core and having annular columns of characters, these characters representing factors and marking along the columns, distances proportional to the tens of the corresponding products and distances proportional to the units of same products.

6. A calculator including a core, rings rotatably mounted thereon, means on the core for holding the ring normally against sliding movement, said means including projecting elements on the core, projections in each ring cooperating with one of said elements for limiting the rotation of the ring, there being a recess in the ring for receiving one of said elements to permit sliding movement of the ring along the core to disengage the projection on the ring, from the element in the path thereof.

7. A calculator including a core, rings rotatably mounted thereon, a non-rotatable sliding sleeve bearing annular columns of characters, these characters representing factors and marking along the columns distances proportional to the tens of the corresponding products and distances proportional to the units of same products, means on the core for holding each ring normally against sliding movement, said means including projecting elements on the core, projections on the ring cooperating with one of said elements for limiting the rotation of the ring, there being a recess in the ring for receiving one of said elements to permit limited sliding movement of the ring to disengage the projection on the ring from the element in the path thereof.

8. A calculator including a core, rings rotatably mounted thereon, each ring containing an annular series of numerals arranged progressively from "0", "1" . . . to "9", a non-rotatable slidable sleeve bearing annular columns of characters, these characters representing factors and marking along the columns distances proportional to the tens of the corresponding products and distances proportional to the units of same products, means on the core for holding each ring normally against sliding movement, said means including projecting elements on the core, projections on the ring cooperating with one of said elements for limiting the rotation of the ring, there being a recess in the ring for receiving one of said elements to permit limited sliding movement of the ring to disengage the projection on the ring from the element in the path thereof.
